Attorneys

oar blade unit 34 pivots to the left about the leg 26. Thus the oar blade unit 34 moves through the water in the same direction as the pull exerted upon the oar handle 46 urging the boat 10 in the direction in which the rower is facing if it is assumed that he has pulled the oar handle 46 toward himself. A push on the oar handle 46 to the right on Figure 1 will similarly urge the oar blade unit 34 to the right also.

In view of the foregoing description taken in conjunction with the accompanying drawings it is believed that a clear understanding of the device will be quite apparent to those skilled in this art. A more detailed description is accordingly deemed unnecessary.

It is to be understood however, that even though there is herein shown and described a preferred embodiment of the invention the same is susceptible to certain changes fully comprehended by the spirit of the invention as herein described and the scope of the appended claim.

Having described the invention, what is claimed as new is:

A bow facing oar comprising a bracket including a bar for mounting on the gunwale of a boat, longitudinally spaced, aligned bearings on said bar, a U-member, comprising threaded legs, having its bight portion journaled in said bearings,

parallel sleeves journaled, at an intermediate point, on said legs, handle and blade oar sections fixed in said sleeves and projecting from opposite ends thereof, said legs passing diametrically through said sleeves and said oar sections, inwardly curved arms on the other ends of the sleeves, a link pivotally connected to said arms, a brace having its end portions journaled on the legs and resting on the sleeves, and retaining nuts, for said sleeves and said brace, threaded on said legs.

LOUIS MAGDITS.
